UNITED STATES PATENT OFFICE.

JACOB STIRISS, OF NEW YORK, N. Y.

ENVELOPE MACHINE.

Application filed August 26, 1921. Serial No. 495,611.

To all whom it may concern:

Be it known that I, JACOB STIRISS, a resident of the city, county, and State of New York, and a citizen of the United States, have invented certain new and useful Improvements in Envelope Machines, of which the following is a specification.

This invention relates to envelope machines and more particularly to machines that shape the envelope from a blank, apply 10 gum to the flap of said envelope or dispense with the gum at the closure and affix a clasp.

The object of the invention is to provide means for either of these operations but to 15 have the means in the machine to disconnect certain parts and confine the work to one of these operations only.

The blank of paper is automatically fed into the machine and is carried through 20 creasing rollers and one of the side edges is gummed in the usual way. It is then delivered to the folding mechanism and folded over a stationary tongue carried by said folding mechanism while its outer free end 25 terminates under the affixing punch. Central pressing rollers play through the tongue and seal the centre seam and deliver the envelope to higher speed rollers connected with a plunger operated by a cam. The 30 purpose of these high speed rollers is to disassociate the envelope from the one following so that the operations for the depositing of a patch and a clasp and other operations may not be interfered with and more 35 time given for same.

The envelope in tubular form encircling the tongue is hastened forward but checked, after it leaves the influence of the high speed 40 rollers, for the said various operations. As the envelope comes to a rest two punches descend and also a roller with gum to supply the bottom flap. One of the punches cuts and affixes a paper patch to the closure flap 45 and makes a perforation in the same while the other forces the prongs of the clasp through the seam of the envelope and affixes the patch of gummed paper over the base of the clasp inside of the envelope, at the same time a second plunger closes the die 50 and prepares a new clasp to be fed in when the affixing punch is at rest.

A blade operating in the vicinity of the gumming roller now descends, as the latter 55 and the punches are elevated, and folds the gummed bottom flap and passes it to multi- 60 lated feed rollers that carry the envelope

from beneath the clasp punch to a third punch which spreads the clasp tongues and ascends as these rollers again take up the envelope and feed it to the final pressing 60 rollers and out of the machine.

Beneath these last rollers is a pair of rollers operating at the same rate of speed as the creasing rollers, one of which carries a gumming plate adapted to collect gum 65 from a gum pot and transfer same to the closure of the envelope.

All of these parts are adjustable and each capable of being thrown out of operation while the other parts continue to work and 70 all are operated from the main drive shaft with adjustable couplings for that purpose.

In the variation of the size of the envelope it is essential that the parts must be adjustable and for this purpose telescopic shafts 75 are used and certain parts mounted on slide bars.

These and other details and objects of the machine are more fully described in the following specification, set forth in the appended claims and illustrated in the accompanying drawings, wherein:

Figure 1 is a side elevation of the improved machine.

85

Fig. 2 is a plan view of the same.

Fig. 3 is a vertical longitudinal sectional view through the rear end of the machine.

Fig. 4 is a cross sectional view through the line 4—4 of Fig. 2.

Fig. 5 is a similar view through the line 90 5—5 and looking towards the front of the machine. Fig. 5^a is a detail view of the moistening wick.

Fig. 6 is a side view of the female die 95 adapted for the machine.

Fig. 7 is the male die for the same.

Fig. 8 is a plan view of the latter.

Fig. 9 is a side view of the flattening plunger.

Fig. 10 is a horizontal sectional view 100 through the flap punch.

Fig. 11 is a vertical sectional view through the clasp punch.

Fig. 12 is a bottom plan view of the same 105 clasp punch.

The improved device embraces features covered by Letters Patent No. 1,371,270 granted to me March 15, 1921, for envelope making machines and in an application for a patent for envelope clasp machines filed January 15, 1921, Serial No. 437,530, and patented November 14th, 1922, #1,435,509,

110

the latter being much simplified in its construction and arrangement of parts.

The blanks for the manufacture of the envelopes are carried by the racks 10 at the front of the machine and separately brought within the range of the creasing rollers 11 by the hollow finger 12, through which air is drawn by a suction pump, and after passing through the said rollers and also receiving the cross grooves when necessary from the cross bars 13 and 14 the blank now ready for folding is passed to the rollers 15 and with the assistance of the rollers 16 that bear upon the rollers 15 and create sufficient pressure to feed the blank forward, it is brought within the influence of the folding plates 17 and the flanges 18 and finally the fingers 19 operating intermittently and closing the folds as the envelope enters the pressing and sealing rollers 20 and 21 as shown in Fig. 4. Gum to seal the folds is supplied by roller 10' from a pot 12' shown in Fig. 2.

The above operation and the operation of the various parts referred to is clearly described in above mentioned Patent No. 1,371,270 and the blank at this stage has its two side flaps folded and closed with the bottom flap and the top or closure flap extended but with the former moving forward and the closure flap trailing rearward for final treatment.

In Fig. 4 it will be seen that the rollers 20 and 21 are each divided at the middle into two end sections to permit of the location of a tongue 22 that is carried by the cross bar 24 that supports the folding plates 17 and said tongue runs through the machine to assist in the various operations that will be further explained. This tongue is slotted to allow the intermediate sealing rollers 20' and 21' on the shafts of rollers 20 and 21 to close the gummed folds of the envelope.

A bed plate 25 with extensions 26 at each side is supported by the frame of the machine and having recesses or pockets 27, 28 and 29, in the former of which plays the roller 21', and the whole plate is movable and adapted to be shifted along the frame by means of the extensions as hereinafter explained. This bed plate carries the two upright frames 30 and 31 with bearings for shafts 32 and 33 having bevelled pinions 34 and 35 that are driven by similar bevelled pinions 36 and 37, the latter actuated by the pinion 38 and shaft 39 from the pinion 34. This train of gears is driven by the bevelled gears 40 and 41 from the main drive shaft 42 (Fig. 1) through the gears 43 and 44 and the upright shaft 45. The shaft 32 has a hand wheel 32' at its end for the purpose of adjustment while the extensions 26 are adjustable lengthwise by means of the rack and pinion 26' at each side of the machine and operated by the handle 27.

In the initial work of the machine it is

necessary that very delicate adjustments be made for the envelope that has been folded and ready for the affixing of the clasp. As the creasing and folding mechanism is practically separate and independent, and blanks of different sizes are at times used the adjustments by the wheels 26' and 32' are indispensable. The humidity of the atmosphere, thickness of the paper and many other causes arise where adjustment is essential.

The shaft 46 carrying the gears 43 and 44 is hollow and in the same plays an extension shaft 47 keyed thereto as shown in Fig. 1, and adapted to rotate a series of bevelled gear wheels 48, 49, 50 and 51 and the shaft 52. Through these wheels are rotated wheels 53 and 54, 55 and 56 and 57 and 58 on the shafts of delivery rollers 59, 60, 61, 62, 63, and 64, the latter being located in the pocket 29 of the bed plate 25 and all the shafts and wheels movable with said bed plate. The latter four gear wheels are rotated by an idler 65 on a stationary shaft 66 and having a pinion 67 that rotates the gear wheel 68 whose shaft 69 carries the gear roller 70 located in the pot 71, as will be seen in Figs. 1 and 3.

The above described gear wheels are carried by brackets 72 suspended by lugs 73 from the extensions 26 at each side of the machine and having appropriate tie rods.

In the roller 63 is a longitudinal groove 74 for the reception of the edge of the folding blade 75 and a part of the circumference of said roller is cut away as at 76 so that at certain times it will not function as a delivery roller for the envelope, but allow the latter to linger while certain operations are being performed by the other parts of the machine.

As shown in Fig. 3 the shaft 69 carries 105 separate and off-set cams 77 and 77' that act at one or both sides of the machine on rollers 78 and 79, the former rollers being located at the ends of arms 80 of the bent arms 81 to the outer end of which the blade 75 is 110 hinged and held normally in the position shown by springs 82 and 82'.

The rollers 79 when they are actuated by the cam 77' swing arms 83 journalled on the shaft 66 and through the roller 84, which they carry, gather glue from the roller 70 and carry it to the bottom flap of the envelope when it rests on roller 63 and before the blade 75 descends. Arms 83 are held against the cam 77' by spring 83'.

The frames 30 and 31 enclose between them the mechanism for punching the clasp and affixing it to the back of the envelope, applying a gummed paper patch to secure the same, spreading the prongs, and applying a reinforcing patch to the closure flap and punching a perforation therein for the tongues of the clasp.

The shaft 33 carries a cam 82 with the face 83 (Figs. 4 and 5) and upon which

plays a roller 84 at the outer end of a lever 85 journalled on the bar 86, in the upper part of the frames 30 and 31 and the lever carries as best shown in Fig. 3, at its other end 5 a plunger 88 and having at its lower end a box 89 with rollers 90 which meet co-operating and continually moving rollers 91 at the upper surface of the bed plate 25. These latter rollers 91 are rotated by the 10 train of gear wheels 92' that operate the rollers 15, 20 and 21 and are shown in Fig. 2 as being driven from the main drive shaft at the front of the machine and synchronously with shafts 45 and 46 as already described but while the latter shafts and the 15 gearing driven thereby may be disconnected by means of clutches 45' and 46', the wheels 92' run continually as they are geared directly from shaft 45 at the side of the machine opposite to Fig. 1.

The driving connections between the main shaft 42 and the train of gear wheels 92' are clearly shown in Fig. 2 of applicant's Patent No. 1,371,270 issued Mar. 15, 1921, and
25 hereinbefore referred to.

The rollers 90 and 91 only operate on the envelope when it is to be advanced and the depression of rollers 90, which forces the envelope against the moving rollers 91, causes the same to move as long as this contact continues. The plunger 88 acts on the roller block 89 by means of the spring 92, but when it moves lower, a head 93 at the lower end of the plunger forces against the closure flap of the envelope and through a suitable opening in the tongue 22 a reinforcing patch that is cut from a roll of gummed tape 94 (Fig. 2) and fed inward by a gripping jaw 95 actuated by a lever 96 and from a cam 97 on the shaft 32, the paper being moistened on its under side and cut by the plunger with an appropriate knife shown in Figs. 3 and 10 and hereinafter described. After this patch is affixed to the flap of the envelope the plunger 88 moves down further and its lower end being a punch, it passes through the tongue 22 and penetrates the flap and patch and makes the hole for the clasp. It will be seen that this operation is possible when the envelope leaves the influence of rollers 90 and 91 and is at rest in consequence of the mutilation 76 of the feed roller 63, as it is also when the succeeding operation takes place.

55 To the rear of this plunger 88 is a second plunger 100 secured near the outer end of a lever 101 that is journalled on a bar 87 and provided at its free end with the roller 102 that rides on the face of a cam 103 on the shaft 32 and as the cam revolves the plunger 100 is forced down and operates the dies, more clearly shown in Figs. 5, 6, 7 and 8, and in which case the male die 104 is placed below and is secured to the ledge 111 of cross bar 105, as shown in Fig. 3, while

the female die 106 is secured to the end of the plunger 100, the die 106 being secured to a bolster 106' and guided by rods 105' on cross bar 105.

Between the two members of the die is 70
adapted to be fed a strip of sheet metal 107
from an appropriate roll at one side of the
machine and a rocking jaw 108 carried by
the slide 109 is adapted to feed at each movement
sufficient metal to make a clasp that is 75
cut off by a knife 110 on the head 127. The
jaw cooperates with the slide 109 that is an
L-shaped block reciprocating on the cross
bar 5 and the strip 107 is passed over the
extension of the block and on which the jaw 80
is depressed to grip the metal strip on the
forward movement but release it when re-
tracted and it is actuated by the rocking
lever 112 pivoted to the frames and carrying
the rod 113 at one end and the roller 114 at 85
the other so that it may travel over the face
of the cam 115 on shaft 32.

While the cutting, forming and inserting of the clasp is fully described and shown in the patent issued to me November 4, 1922, for envelope-clasp punching and affixing machines and bearing Patent Number 1,435,509, the following brief description of the forming of the clasp in the present instance may be sufficient. 90 95

In forming this clasp the strip is first slit by the cutting die 116 (Figs. 7 and 8) and punched by the projections 117 with two upwardly extending prongs and when the cut clasp is released it falls upon the gummed side of a strip of paper 118 (Fig. 5) that is intermittently fed towards the centre of the machine by the sliding tank 119 and jaw 120, the latter being identical to the jaw 95 for paper strip 94 and pivoted above an identical tank on the other side of the bar 105 so that with the forward movement of rod 121, through the medium of the lever 122 and cam 123, the strip is intermittently moved forward and released. Both of these strips of gummed paper are moistened by wicks 124 and 124' from the small tanks 119 but while strip 94 is moistened on its under side when its slotted wick 124' is raised, strip 118 is moistened by the wick on its upper side and is delivered as a patch on the tongue 22 with the clasp on the same just before the envelope reaches that point.

The punch 116 is convex on its upper face for the purpose of shearing the strip through its centre and preparing it for the punches 117 as it is fed forward by the jaw 108 and the latter punches then cut and bend the prongs upward. The next feed of the strip carries the unsevered clasp beneath the plunger head 127 which on its descent in its first operation will slightly wedge the prongs in its cavity and hold the clasp when the knife 110 parts said clasp from the strip 107. 120 125 130

It will be seen in Fig. 7 that the upper face of punches 117 are inclined so as to not only cut the prongs but to bend them upward as shown in dotted lines in Fig. 11.

- 5 When the clasp is thus located in the head 127 the moistened strip 118 also has been advanced so that its end is beneath said head whose downward movement with the knife 143 severs the patch and carries it
 10 with the clasp to the upper side of the tongue 22. The proximity of the metal and gummed strips and the limited space between the head and the tongue insure the proper positioning of the two on the tongue for
 15 the approaching envelope and the operation of attaching the same is hereinafter more fully explained. After this operation the cam permits the plunger and head to ascend so that the envelope may be moved into
 20 position to receive the clasp.

During these operations the envelope is as a tube travelling on the said tongue and enclosing the same and it will be seen in Fig. 3 that the tongue is provided with a
 25 flexible lip 125 near the point where the dies are located and this lip is to expand the envelopes so they will pass that point without disturbing the clasp and its patch and as soon as the appropriate part of the envelope
 30 reaches this point a second operation of the plunger 126 through cam face 103^b takes place on the clasp with its upright prongs, forces them through the overlapping folded sides of the envelope and causes the gummed
 35 patch to adhere to the envelope and secure the clasp.

It will be seen in Figs. 4 and 5 that the cam 103 has two differently elevated faces 103^a and 103^b and the former cuts the clasp and paper strip which drop on the tongue 22 while the second face 103^b causes plunger 126 to move down farther and forces and affixes the clasp in the envelope and acts upon the die, the spring 145 providing yielding action for the head 127 while the die is cutting a new clasp blank.

The machine is adapted for producing a clasp of elongated rectangular shape and it is evident therefore that the patch for the
 50 same must be larger than the clasp base and extend around all of its edges.

The plunger 126 is located at the extreme outer end of the lever 101 and carries the spring pressed head 127 in which it telescopes in order to exert a yielding pressure and the affixing operation is performed on the tongue 22 and to more thoroughly secure the clasp and spread its prongs it is subjected to the last plunger 128 with yielding head 129, see Fig. 9, that operates upon the tongue 22 and drives upon the clasp before the envelope leaves the tongue 22. The latter plunger is operated by a lever 128' on shaft 86 and by cam 129' on the shaft 33, and works in its proper sequence.

During these operations of the plungers the envelope is being carried bottom forward towards the rollers 63 and 64 and the bottom folder and forced between the said rollers by the blade 75 but its movement hesitates in consequence of the cut-away portion 76 and at that moment plunger 128 operates and after which the envelope is caught by rollers 59 and 60, and passed out.

The machine as thus described is adapted to produce an envelope without gum on its closure flap but with the clasp only for that purpose, but when it is desired to dispense with the clasp, the clutch 45' is permitted to release the shaft 45 and render the plungers 75 inoperative and the envelope will be made and while passing through the rollers 59 and 60 is impinged by a relief plate 130 that gathers glue from a supply on the fountain roller 132 located in the pot 133. The roller 132 may be rotated by its pulley wheel 134 that is driven by the pulley 135 on the shaft 52 and through a belt, while the plate 130 is adapted to meet a depression 136 in roller 60 and not mar the same if the blanks fail to be fed into the machine. The ends of the plate are slotted and through the slots are passed adjusting screws 137 to withdraw the plate from operation if the gluing is dispensed with.

The machine may also be adapted for the manufacture of envelopes without either gum or clasp by thus rendering the plate 130 inoperative, so it will be seen that the machine is capable of three different 100 productions.

After each envelope is completed it is dropped on the conveyor belt 138 to be carried to some convenient place for stacking and packing.

Referring to Figs. 3 and 10 it will be seen that the head 89 of the plunger 88 is carried in a bearing of cross bar 105 and has secured to it a knife blade 139 on the side from which the gummed paper is fed while a blade 140 that is loosely attached to the bed 25 but held in place by pins 141 and compressed against the co-operating blade 139 by springs that encircle the pins is provided.

As will be more clearly seen in Fig. 4 while the paper feeders and moisteners are similar the jaws 95 and 120 are reversed so that the former moistens the strip on the under side to apply it to the flap while jaw 120 moistens it on the upper side to receive the clasp and to gum the patch to the inner side of the envelope. In both of these cases the moistening wick is appropriately placed on the side of the strip to be moistened and a portion of it hangs into the pan 119.

In Fig. 5^a the construction of jaw 95 is more clearly shown and shows the wick 124' as having an opening through which the strip 94 travels and the depending edges of

the wick gathers up the moisture from the tank for the impinging portion.

The wick 124' is perforated for the passage of the gummed strip and rises and lowers with the jaw 95. The latter in its forward movement advances the strip and on the return movement frees it and the wick is raised with the jaw and while the strip is at rest the returning wick will impinge its lower side.

The clasp and patch affixer is more clearly shown in Fig. 11 where it will be seen that the head 127 carries a blade 110 for the metal strip and a blade 143 on the opposite side for the gummed paper strip. Yielding pins 144 are also provided to play within the head and to force the clasp and paper patch downward on the tongue to be properly located when the envelope reaches the position for the clasp's location. In Fig. 5 is shown how the head 127 is carried on the lower end of the plunger 126 with an intervening spring 145 to exert a firm but resilient pressure to enable the head to play in the nest 127'.

The nest 127' is located between the cross bar extensions 105 and is larger at its lower end than above because the paper patch is the larger and the movement of the clasp must be limited thereby so that it is not misplaced on the patch or the tongue. Fig. 12 shows the plunger and nest from the bottom. To aid the patch and the clasp to retain their proper positions on the tongue 22 a small tube 145' is run the length of the tongue to some air exhauster and opens directly below the place where the patch and clasp drop after being cut to hold them by suction. When the clasp is made of steel a magnetic block is used to hold the clasp and patch in place.

In order to prevent too great a movement of the envelope after the impetus given it by the rollers 90 and 91 and after it leaves their influence, a friction spring 125' is secured to the under side of the tongue to bear against the envelope and pressing it against the bed.

It is obvious that various forms of envelopes and clasps or closures may be made and attached by modifications of the mechanism above described yet without departing from the essential features shown or departing from the scope of the appended claims.

What I claim as new is:

1. In a clasp-envelope machine, the combination of rollers comprising feeding and creasing means, folding means, a plunger adapted to affix the clasp in the back of the envelope, means for affixing a reinforcing patch to the flap of the envelope, and a punch adapted to perforate the reinforcing patch.

2. In a clasp-envelope machine, the com-

bination of feeding and creasing rollers, folding means for an envelope blank, supporting means adapted to have the envelope formed around it, a plunger for cutting a metal clasp, a plunger for affixing the same to the envelope, means for cutting a gummed paper strip and affixing it within the back of an envelope, and a punch to perforate the flap of the envelope.

3. In a clasp-envelope machine the combination of means for creasing and means for folding the sides of the envelope, means for feeding a strip of metal, means for feeding strips of gummed paper, a plunger adapted to cut and form clasps from the metal strip, a plunger having a knife adapted to cut reinforcing patches from the paper, and affix the same, a punch adapted to perforate the same, and feeding means for the envelope.

4. In a clasp envelope, the combination of creasing and folding means, intermittent feeding means, means for feeding a strip of sheet metal, means for feeding a strip of gummed paper, a plunger adapted to form and cut a clasp from the sheet metal, a second plunger having means adapted to cut a patch from the gummed paper, and means for affixing the clasp and the patch of paper.

5. In a clasp machine, the combination of creasing and feeding means, folding means for the sides of the envelope, means for sealing the said sides together, a tongue adapted to support the envelope in a tubular form, means for cutting a clasp and depositing the same on the tongue, a plunger adapted to force the prongs of the clasp through the back of the envelope, means adapted to cover the inside of the clasp with a retaining patch, and means for flattening the clasp on the back of the envelope.

6. In a clasp-envelope machine the combination of creasing means and folding means for the envelope blank, means for supplying gum to the latter, means for sealing the folded sides of the envelope, means for forming and cutting a clasp for the envelope, means for enclosing the same in the incomplete envelope, a plunger adapted to force the prongs of the clasp through the said incomplete envelope while in tubular form and means for flattening the clasp.

7. In a clasp-envelope machine, the combination of creasing means and folding means, means for supplying gum to one of the edges of the envelope, pressing rollers to seal the same, a tongue adapted to carry the incomplete envelope, intermittent feed rollers, a plunger carrying the same, a knife operated by the plunger, a strip of gummed paper adapted to be cut as a reinforcing patch and affixed to the flap of the envelope by the plunger, a punch in the

plunger adapted to perforate the flap and the patch, and means for cutting and affixing a metal clasp.

8. In a clasp-envelope machine, the combination of means for creasing an envelope, means for gumming the same, folding means for the envelope; a tongue adapted to be enclosed in the incomplete envelope, intermittent feeding means for the said incomplete envelope, a patch affixing plunger, a plunger adapted to cut from a strip and locate a metal clasp and cut a retaining patch, a plunger adapted to flatten the clasp, a punch adapted to perforate the first patch and creasing and folding means for the end flaps.

9. In a clasp-envelope machine, the combination of means for creasing the side flaps of the envelope, means for folding the same, means for applying gum to one of the flaps, means for spacing the front and back of the envelope, means for inserting a metal clasp with its prongs extended upward in the said spacing, means for forcing the prongs outward through the incomplete envelope, means for flattening the prongs on the outside of the back of the envelope and means for inserting a retaining patch beneath the clasp and within said envelope.

10. In a clasp envelope machine, the combination of creasing means for an envelope blank, means for folding the flaps of the envelope along the creases, means for applying gum to one of the flaps, a plunger carrying rollers, co-operating feed rollers for the rollers of the plunger, a punch at the end of said plunger, a second plunger, a die at the end of said second plunger and adapted to form a clasp from a strip of metal, a third plunger, means carried by the latter adapted to cut the clasp from the strip of metal and apply it to an incomplete envelope, means of the third plunger adapted to cut a patch of paper from a strip to be applied to the incomplete envelope by the plunger, a fourth plunger adapted to flatten the clasp in the incomplete envelope, means for applying gum to an end flap of the envelope, and means for folding and sealing the latter flap.

11. In a clasp envelope machine, the combination of creasing means for the sides of an envelope blank, means for applying gum to one of the sides, means for folding the sides, sealing rollers, intermittent advancing rollers operated by a plunger, a punch operated by the same plunger, forming dies for a clasp, a plunger adapted to cut and affix the clasp and a protecting patch, a flattening plunger, a creasing blade for the end flap of the envelope, an intermittent gum roller for said flap, and sealing rollers.

12. In a clasp-envelope machine, the combination of rollers adapted to seal the folded sides of an envelope, a plunger carrying a spring pressed head with advancing rollers, a knife operated by the head, a punch at the

lower end of the plunger, a cam adapted to reciprocate the plunger, clasp cutting and affixing means, a gumming roller intermittently operated to supply the bottom flap of the envelope with an adhesive, a gum supply pot adjacent the roller, an intermittently operated blade adapted to crease and fold said bottom flap; and sealing and feeding rollers adapted to seize the envelope from the blade.

13. In a clasp envelope machine, the combination of rollers adapted to seal and feed an envelope blank, a tongue adapted to carry the incomplete envelope, a spring finger on the tongue and adapted to separate the back from the front of the envelope, punch carrying intermittent feeding rollers, means for feeding a strip of gummed paper, dies carried by a plunger and adapted to form a clasp on a strip of metal, a plunger adapted to cut the clasp from the strip and affix it to the incomplete envelope, means for cutting a patch from the strip of paper and affixing it to the inner side of the clasp, and a plunger with means adapted to spread and flatten the clasp on the envelope.

14. In a clasp-envelope machine, the combination of an oscillating lever, a plunger carried by the same and having dies for punching a clasp, feeding means for a strip of sheet metal adjacent the dies, a second plunger carried by the lever and adapted to cut the clasp from the strip and force its prongs through the envelope, means carrying a strip of gummed paper, a knife on the second plunger and adapted to cut a patch from the strip of paper, and means for spreading and flattening the clasp when affixed to the envelope.

15. In a clasp-envelope machine, the combination of upright frames, shafts between the same, motive means for the shafts, cams on the shafts, a plunger with intermittent feeding rollers and operated by one of the cams, a punch and a knife operated by said plunger, a plunger with dies and affixing means operated by a cam, a plunger with a collapsible spreading head operated by a third cam, feeding means for a strip of sheet metal operated by a cam on a shaft, feeding means for strips of gummed paper and operated by cams on the shafts, rollers adapted to carry gum for the flaps of the envelope, and intermittent feed rollers.

16. In a clasp-envelope machine, the combination of a roller and pot for applying gum to the side flap of an envelope, means for folding the flap, means for sealing the flap, clasp cutting and affixing means, intermittent feeding rollers, a gum applying roller and gum pot for the bottom flap of the envelope, a folding blade and sealing rollers, and a roller with means adapted to apply gum to the closure flap of the envelope as it passes through the machine.

17. In a clasp envelope machine, the combination of means for creasing the sides of an envelope, means for folding the said sides, means for sealing the same, a member adapted to have the envelope folded about it, means for forming a metal clasp having prongs and depositing it on the member, means for cutting a paper patch and depositing it on the same member, and means for spreading the prongs of the clasp. 10
18. In a clasp envelope machine, the combination of envelope folding means, means for forming a metal clasp, means for attaching the same to an incomplete envelope, means for cutting a patch from a strip of gummed paper, means for applying the same to the inside of an envelope, and means for punching a perforation for the prongs of the clasp and means for surrounding the same with a reinforcing border. 20
19. In a clasp envelope machine, the combination of means for folding the side flaps of an envelope, means for forming a clasp on a metal strip, means for cutting the clasp from the strip and securing it in the unfinished envelope, means for cutting and applying a protecting patch within the envelope and back of the clasp, means for applying a reinforcing patch to the flap of the envelope, means for perforating the flap and patch, means for folding the bottom end flap of the envelope, and means for sealing the same. 30
20. In a clasp envelope, the combination of folding means for the sides of the envelope, intermittent feeding means, means for forming a clasp from a strip of metal, means for detaching the clasp from the strip and affixing it to the unfinished envelope, means for cutting a patch of gummed paper from a strip, means for applying the patch to the inside of the unfinished envelope, means for cutting a patch of paper from a strip of gummed paper and applying it to a flap of the envelope and perforating same, all as the envelope is intermittently moved through the machine. 45
21. In a clasp envelope machine, the combination of means for intermittently moving an unfinished envelope through the machine, means for folding the sides of the envelope, means for sealing the closed sides of the envelope, means for affixing a metal clasp, means for applying a protecting patch to cover the inner side of the clasp, means for applying a reinforcing patch to the flap of the envelope and means for punching a perforation through the patch and the flap, all the operations being performed as the envelope is intermittently passed through the machine. 50
22. In a clasp envelope machine, the combination of means for intermittently feeding an unfinished envelope through the machine, means for folding its sides, means for sealing the sides together, means for forming a clasp, means for cutting the same from a strip of metal and affixing it to the unfinished envelope, means for securing a protecting patch within the envelope and over the clasp, means for applying a reinforcing patch to the open flap of the unfinished envelope, means for perforating the same, means for pasting the bottom end flap, means for folding same and means for sealing same after being folded, all of the operations being performed as the envelope intermittently passes through the machine. 65 70 75

In testimony whereof I hereunto affix my signature.

JACOB STIRISS.
